UNITED STATES PATENT OFFICE.

EDWARD WILLIAM GOODRICK, OF APPLETON, WISCONSIN.

BARK-ROSSING MACHINE.

No. 838,102.

Specification of Letters Patent.

Patented Dec. 11, 1906.

Application filed January 8, 1906. Serial No. 295,049.

To all whom it may concern:

Be it known that I, EDWARD WILLIAM GOODRICK, a citizen of the United States, and a resident of Appleton, in the county of Outagamie and State of Wisconsin, have invented certain new and useful Improvements in Bark-Rossing Machines; and I do hereby declare that the following is a full, clear, and exact description thereof.

10 My invention consists in certain peculiarities of construction and combination of parts hereinafter particularly set forth with reference to the accompanying drawings and subsequently claimed, its object being to improve bark-rossing machines of the kind employed in the preparation of log-sections, commonly termed "blocks," for the reduction of same to paper-pulp, the improvement having especial reference to adjustment of the block-rest of such a machine.

Figure 1 of the drawings represents a side-elevation of an improved bark-rossing machine in accordance with my invention, partly in section; Fig. 2, a front elevation of the machine, partly in section; Fig. 3, a plan view of said machine, and Fig. 4 a horizontal section of a fragment of same.

Referring by letter to the drawings, A indicates a preferably hollow stand having a front upper hood extension B, provided with a rectangular front aperture. The stand is provided with oil-box bearings for a shaft C, and fast on this shaft within said stand and the hood extension thereof is a knife-disk D, facing the aperture aforesaid. The shaft is herein shown provided with tight and loose pulleys E F for a driving-belt; but any suitable means may be employed to drive said shaft. A stop-gage G is shown in adjustable connection with the front of the hood B adjacent to one end of the aperture in same, and as thus far described the machine is similar to those of common knowledge for the purpose above specified.

45 In accordance with my invention the front of the machine is provided with a lower central vertical rack H and a pair of vertical guides I for parallel bars J, equidistant from the rack. The vertical bars are provided with upper arm extensions K, herein shown at right angles thereto toward the operator of the machine. Extending through the arms is a rod L, provided with collars b, that abut the inner sides of said arms, and nuts c are run on the ends of the rod against the outer sides of the aforesaid arms.

Bolted to lower lugs d of the bars J is a front plate M, having a central aperture, and hung in pivotal connection with ears e of the plate is crank-dog N, that plays in said aperture and engages the rack I aforesaid.

The bars J, their horizontally-disposed arms K, the rod L, and plate M constitute a block-rest frame that is readily adjustable in a vertical direction to support a block thereon in position to be acted upon by the knife-disk of the machine, said block-rest being held in its adjusted position by an engagement of the dog N with the opposing rack. By taking hold of the rod L the block-rest 65 may be lifted to a desirable elevation, the dog N catching in the rack H to maintain the adjustment. To lower said block-rest, the same is lifted slightly and the dog N disengaged from the rack H by a foot of the operator, after which the desired adjustment is effected and said dog again permitted to engage said rack.

Machines of the kind above noted are ordinarily provided with block-rests in the form 80 of brackets bolted in adjusted position, and to vary the adjustment of such block-rests requires an undesirable expenditure of time that may be saved by the employment of the novel construction and arrangement of parts 85 herein shown and described in order to accommodate the machine to blocks of varying diameter.

A block supported on the rest is turned by hand in contact with the knife-disk of the 90 machine, the result being a shaving of the bark from said block.

While I have shown the locking-dog arranged to engage a rack on the front of the machine, other provision may be had with 95 the dog for holding the block-rest in adjusted position.

I claim—

1. A bark-rossing machine comprising a rotary knife-disk and having the front thereof provided with a vertical rack and guides, bars engaging the guides and having upper arms extending therefrom toward the operator of the machine, a rod connecting the arms, a lower apertured plate connecting the 100 bars, and a dog hung in connection with the plate to play in the aperture of same and engage the rack.

2. A bark-rossing machine comprising a stand provided at the front with a vertical 110 rack and guides, a frame having side bars thereof in sliding engagement with the guides

and provided with horizontally - disposed block-supporting arms extending toward the operator of the machine, a dog hung in connection with the frame to engage said rack, 5 and a suitably-arranged rotary knife-disk fast on a shaft for which said stand is provided with bearings.

In testimony that I claim the foregoing I

have hereunto set my hand, at Milwaukee, in the county of Milwaukee and State of Wisconsin, in the presence of two witnesses.

EDWARD WILLIAM GOODRICK.
